UNITED STATES PATENT OFFICE.

WILLIAM H. PEIRSOL, OF PHILADELPHIA, PENNSYLVANIA, ASSIGNOR OF ONE-HALF TO JAMES L. PEIRSOL AND WINFIELD S. PEIRSOL, OF SAME PLACE.

DESIGN FOR AN EGG-CUP.

SPECIFICATION forming part of Design No. 27,133, dated June 1, 1897.

Application filed March 27, 1897. Serial No. 629,620. Term of patent 14 years.

To all whom it may concern:

Be it known that I, WILLIAM H. PEIRSOL, a citizen of the United States, residing in the city and county of Philadelphia, State of Pennsylvania, have invented and produced a new and original Design for Egg-Cups, of which the following is a specification, reference being had to the accompanying drawings, forming part thereof.

10 The leading feature of my design for an egg-cup is an exterior cup having an inner vessel occupying the same.

Figure 1 represents a perspective view of an egg-cup embodying my design. Fig. 2

represents a partial vertical section and partial side elevation thereof.

In the drawings, A designates an exterior cup, and B designates an inner vessel, which is suspended by the top C within the former and partly occupies the same.

What I claim is—

The design for an egg-cup substantially as described and shown.

WILLIAM H. PEIRSOL.
